(57) **CLAIM**

The ornamental design for a gun stock with accessory rail, as shown and described.

DESCRIPTION

FIG. 1 is a perspective view of a gun stock with accessory rail in accordance with my new design;

FIG. 2 is a front left bottom perspective view of the gun stock with accessory rail of FIG. 1;

FIG. 3 is a front view of the gun stock with accessory rail of FIG. 1;

FIG. 4 is a rear view of the gun stock with accessory rail of FIG. 1;

FIG. 5 is left side view of the gun stock with accessory rail of FIG. 1;

FIG. 6 is a right side view of the gun stock with accessory rail of FIG. 1;

FIG. 7 is a top view of the gun stock with accessory rail of FIG. 1; and,

FIG. 8 is a bottom view of the gun stock with accessory rail of FIG. 1.

All portions shown in broken lines are environmental and illustrative only and form no part of the claimed design.

1 Claim, 6 Drawing Sheets
